UNITED STATES PATENT OFFICE.

LOUIS S. TENENBAUM, OF ROCHESTER, NEW YORK.

ASH-SIFTER ATTACHMENT FOR FIRE GRATES.

Application filed December 8, 1926. Serial No. 153,275.

The object of this invention is to provide an attachment for fire grates by means of which the ashes from the fire box are automatically sifted while the grate is being shaken to clean the fire.

This and other objects of this invention will be fully illustrated in the drawings, described in the specification and pointed out in the claims at the end thereof.

10 In the accompanying drawings:

Figure 1 is a front elevation of a series of grate bars with the ash sifter suspended underneath it and attached thereto.

15 Figure 2 is a vertical longitudinal section through the section of grate bars and the ash sifter suspended underneath it and connected thereto.

20 Figure 3 is a front elevation of a series of grate bars showing a modified form of connection between the grate bars and the ash sifter.

Figure 4 is a perspective view of a modified form of the ash sifter.

25 Figure 5 illustrates a modified locking bar for locking and unlocking the trap door in the bottom of the wire basket.

In the figures of the drawings like reference numerals indicate like parts.

30 In order to burn coal economically it is necessary to separate from the ashes the unburned pieces of coal that pass through the grate with the ashes. For this reason separate ash sifters are universally used through which the ashes taken from the 35 grate are passed before they are finally thrown away. In these ash sifters the particles of unburned coal are separated from the ashes proper so that the ashes can be thrown away and the coal used over again 40 in the furnace or boiler. In the use of these ash sifters it is necessary to handle the ashes twice, that is the ashes are shaken through the grate and dropped into the ash box from which they must be shoveled into the ash 45 sifter and sifted. After this is done the ashes and coal must be separately shoveled from the separator and disposed of a second time.

50 The invention forming the subject matter of my present invention comprises an ash sifter that is directly attached to the grate bars and suitably connected thereto so that on the operation of these bars for the purpose of cleaning the fire the particles of unburned coal are separated from the ashes be-

fore the ashes have dropped into the ash box.

As illustrated in the figures of the drawing the ash sifter comprises the wire basket 1. This basket is suspended at the front and back from the grate bars 2, 2. For this purpose suitable hooks 3, 3 are provided both at the front and back of the basket 1 which hooks are adapted to engage around the cylindrical portion of the grate bars so as to 55 freely suspend the basket underneath them. To operate the ash sifter formed by the basket 1 the swinging bar 4 is provided. This bar is suspended centrally of the basket 1 near the front thereof and its lower end 60 extends through a slot 5 in the bottom of the basket 1.

The upper end of the swinging or rocking bar 4 has the links 6 and 7 pivotally attached thereto by means of which the bar is rocked 65 as will presently appear. The outer ends of the links 6 and 7 partially encircle the cylindrical portion of a grate bar and are supplemented by a strap 8 that is suitably hinged thereon and is adapted to encircle 70 the remainder of the grate bar which is then clamped to the link by a suitable locking bolt 9. A set screw 10 which is threaded into the strap 8 is then tightened against the 75 grate bar in order to firmly lock the end of the link to the bar to make it swing on the 80 rocking of the grate bar.

The rocking or swinging bar 4 is thus suspended between two grate bars and on the 85 rocking of either one of them the link attached thereto will rock the rocking bar in unison with it and transmit to the basket an oscillating motion which reciprocates the basket sideways. As the ashes drop through the grate bars into the basket they are thus 90 shaken within the basket and are sifted as soon as they reach the basket. On shaking the basket the fine ashes drop through the wire mesh of the basket while the larger 95 lumps of unburned coal remain in the basket and accumulate therein. In this way the 100 fine ashes are quickly separated from the unburned pieces of coal every time the grate is operated. The ashes thus deposited in the bottom of the ash box have therefore no 105 further value and when shoveled out are ready to be put into the ash can. The coal within the basket on the other hand may be fed back into the fire box. For this purpose the bottom of the basket is provided 110

with a trap door 19 that is hinged at the rear of the basket on the inside.

The front of the trap door is provided with a hook 20 which is suitably hinged 5 thereon so that it can be moved into or out of engagement with the upper edge of the basket 1. When engaging the basket as illustrated in Figures 1 and 2 the trap door 19 is held closed by the hook 20 so that the 10 ashes that accumulate therein are sifted as the basket is oscillated. When it is desired to remove the coal accumulated within the basket, the trap door is released by unhooking the hook 20 which allows the trap door 15 to drop down into the dotted line position illustrated in Figures 1 and 2. The coal accumulated in the basket then slides out through the trap door and onto a shovel that may be placed under the basket 1 before the 20 trap door is released. The basket 1 is mounted below the grates so that it can be readily and bodily detached from them if so desired, in which case the coal accumulated therein may be taken out from below the 25 grates in the basket and the basket emptied onto the shovel or into a suitable receptacle. After the basket is emptied it is again put in place underneath the grates.

In order to prevent the coal from dropping off on the sides of the door a series of 30 chains 21 and 22 is provided on each side of the door and connected to either the bottom or top of the basket so that when the door is opened these chains form a flexible 35 partition between the door and the basket that prevents any coal from dropping off the sides of the door.

Instead of using chains 21 and 22 the trap door may be made as illustrated in Figure 4 40 in which triangular sides 23 and 24 are formed integral with the door which move up and down with the door and prevent the coal from dropping off on the sides of the door when the door is open.

45 In smaller furnaces or boilers fewer number of grate bars are used and in such cases only one of the grate bars is rocked in order to clean the fire. Such a grate is illustrated in Fig. 3 and in this case the rocking bar 50 15 instead of being connected to two grate bars by means of suitable links it is attached directly to the grate bar that is oscillated. In this way the basket 1 is operated on the operation of the one grate bar.

55 In Figure 5 I have shown a modified form of the locking bar 25 for locking the trap door in place in the bottom of the basket. This locking bar 25 may be used in place of the hook 20 and is swiveled at the bottom of 60 the basket at the front end thereof. By turning this bar the end thereof may be either withdrawn from under the door to allow the door to drop down for the purpose of emptying the basket or the end of 65 the bar may be turned to engage under the

door after the basket is emptied and hold the door in place in the bottom of the basket to allow more coal to accumulate therein.

I claim:

1. In an ash sifter attachment for fire 70 grates, the combination of a wire basket, means for freely suspending said wire basket below a series of grate bars a rocking bar, suspended from one of said grate bars and slidably engaging said basket, so as to shake said basket on the shaking of the grate bar.

2. In an ash sifter attachment for fire 80 grates, the combination of a wire basket, hook members supporting the front and back of said basket below a series of grate bars, a rocking bar, a pair of links pivotally connected to the top of said rocking bar and projecting to either side thereof, each of 85 said links being fastened to a grate bar, the lower end of said rocking bar engaging said basket to shake said basket on the shaking of either one or the other of the grate bars having one of said links fastened thereto.

3. In an ash sifter attachment for fire 90 grates, the combination of a wire basket, hook members for freely suspending said wire basket from the grate bars of said fire grate, means for horizontally reciprocating said wire basket on the oscillation of one of 95 said grate bars, a trap door hinged in the bottom of said wire basket, and means for locking and unlocking said trap door in the bottom of said wire basket.

4. In an ash sifter attachment for fire 100 grates, the combination of a wire basket, hook members for freely suspending said wire basket from the grate bars of said fire grate, a trap door hinged in the bottom of 105 said wire basket, means for locking and unlocking said trap door in the bottom of said wire basket, and means provided on the sides of said trap door to prevent particles of coal from dropping off from the sides of the trap door on the release of said trap door.

5. In an ash sifter attachment for fire 110 grates, the combination of a wire basket, freely swinging hook members at the front and back of said basket adapted to pivotally engage the grate bars with one end and the wire basket at the other end to freely suspend said basket from a series of grate bars, said basket having a hole therein, a 115 rocking bar adapted to be attached to one of the grate bars and having a sliding engagement with the hole in said wire basket, said rocking bar reciprocating said wire basket on the oscillation of the grate bar, a 120 door pivoted in the bottom of said basket and sides provided on said door to connect the door with the bottom of the basket when the door is opened.

In testimony wherof I affix my signature.
LOUIS S. TENENBAUM.
